MULTIOFFICE TELEPHONE SYSTEM

Application filed May 31, 1929. Serial No. 367,168.

This invention relates to multi-office telephone systems in general, but is concerned more particularly with multi-office telephone systems in which calls are completed through the medium of automatic switches and in which certain classes of calls are extended by an operator. The main features of the invention relate to improved apparatus of the so-called "universal switcher" type and associated apparatus for use in multi-office systems employing satellite or sub-exchanges and to improved trunk circuits and operators' circuits for use in systems of this kind.

The economic reasons for employing satellite or sub-exchanges are well known and will not be discussed here. Sub-exchanges usually have installed only originating and terminating apparatus such as lineswitches and connectors while the switches of the intermediate switching stages are located in the main exchange. All calls originating in the sub-exchange are, therefore, trunked to the main exchange where office and group selection is made. This is the case in both local and outgoing calls, and obviously, trunking facilities are going to be tied up in local connections unless special provision is made to prevent it. A number of ways of releasing the trunking apparatus on local calls have been devised of which that employing the so-called universal switcher is one of the most satisfactory. The main function of this apparatus is to register one or more digits of the called number as required to identify the call as local or outgoing and to perform the necessary switching operations to release the switches not absolutely required in the final connection. Universal switching apparatus is thoroughly described and its utility set forth in United States Patents Nos. 1,623,320 to Smith, and 1,682,158 to Willis. The features of this invention relating to the universal switcher may be considered as an improvement on the latter patent.

The provision of restricted service for certain classes of subscribers is also old and well known although as far as applicants are aware its application to sub-exchange systems employing universal switchers has never been entirely successful. This is due primarily to

the fact that one or more digits must be dialled before the call can be identified as local or outgoing and in the case of calls from non-restricted lines, these digits must also operate switches in the main exchange. It is desirable for various reasons that attempted trunk calls from restricted lines be intercepted by an operator who can then complete the call as a toll call or inform the calling subscriber that service is denied.

The object of the invention, broadly stated, is to improve systems of the above general character by the provision of new and improved circuits and apparatus for performing the necessary switching operations efficiently and economically.

One feature of the invention relates to simple and efficient circuits for use in connection with universal switcher type sub-exchanges in which both restricted service and non-restricted service is furnished. These circuits provide for the interception of attempted trunk calls from restricted lines and the automatic trunking of such calls to an operator.

Another feature of the invention relates to an improved universal switcher for sub-exchange working arranged so that local calls may be completed regardless of the busy or idle condition of the inter-office trunks.

Another feature of the invention relates to highly efficient trunk circuits over which toll service may be given and which also serve as intercepting trunks, one of the principal advantages being the arrangement whereby an operator may control switches in the distant exchange over the same trunk by which the call was extended to the manual position, the calling subscriber meanwhile waiting on the line.

Another feature of the invention relates to new connector circuits particularly adapted for small exchange use. These connectors are of the type whose wipers move only in one plane.

Still another feature relates to an improved trunk hunting switch of the rotary type adapted to connect with either of two classes of lines as required by the particular connection in which it is used.

The foregoing features together with 100

others not specifically mentioned will be described in detail hereinafter, reference being had to the accompanying drawings comprising Figs. 1 to 8, inclusive. The drawings show by means of the usual circuit diagrams a sufficient amount of the equipment in a multi-office telephone system embodying the features of the invention to allow the invention to be readily understood.

- 10 In order to make the description as simple as possible, the application of the invention to a telephone system comprising three exchanges will be described. It is to be understood, however, that the application of the invention is not limited to this particular arrangement but that it may be used with other combinations of equipment and in systems comprising a different number of exchanges from that described herein.
- 20 The equipment located in the sub-exchange is shown in Figs. 1, 2, and 3. The equipment in the main exchange which is also an automatic exchange is shown in Figs. 4, 5, 6, and the left-hand portion of Fig. 7. The apparatus in the right-hand section of Fig. 7 is located in the third exchange which is assumed to be a manual exchange or toll office. Fig. 8 is a layout diagram showing how the sheets on which Figs. 1 to 7, inclusive, are drawn should be placed together in order to be understood best.

Referring now to Fig. 1, T represents an ordinary automatic substation associated with a lineswitch which terminates in a group of line relays LR at the sub-exchange. Start relays STR are common to all lines in the sub-exchange and initiate the operation of the finder switches such as switch F which has access to the subscribers' lines. The finder switch F is associated with a switching repeater SR which is shown in detail. Other switching repeaters SR', SR'', SR''' are shown as rectangles with only enough of their apparatus as is required to illustrate their inter-relation. It will be understood, of course, that there are a number of lines such as that extending to substation T and also a number of finder switches and repeaters in the exchange. In addition to its function as a trunk repeater, repeater SR is equipped with mechanism for recording the first two digits of a call. The purpose of this is to provide for certain switching operations in case the call is for a subscriber located in the sub-exchange.

In Fig. 2 is shown a double-hunting lineswitch DLS of the rotary lineswitch type. This lineswitch terminates a trunk from the repeater such as repeater SR shown in Fig. 1. The lineswitches such as switch DLS have access to local and outgoing trunks and to separate sets of contacts which are made available for selection in case all trunks of one class or the other are busy. The local trunks terminate in local connectors, such as LC, which

has access to the lines in the sub-exchange. Connector LC is mechanically similar to the well known rotary lineswitch. The circuit is similar to that of the ordinary Strowger type connector with certain modifications which are a part of this invention and will be described in detail hereinafter.

Fig. 3 shows an incoming connector IC through which is multipled an outgoing trunk extending from the banks of lineswitch DLS to the main exchange. Connector IC is similar to connector LC, except for certain modifications required due to its use as an incoming switch. One incoming connector is provided for each trunk from the main exchange. T1 represents another subscriber's substation in the sub-exchange. The line from substation T1 will also terminate in a group of line relays such as LR, (not shown) accessible to line finders such as finder F.

In Fig. 4 is shown an incoming repeater DR associated with the trunk from the sub-exchange. Associated with this repeater are a number of other trunks of which one extends to an incoming selector in the main office, another to the bank of an intercepting trunk finder switch, and another extends to the banks of the local selectors in the main office.

In Fig. 5 is shown the regular equipment in the main office. With the exception of lineswitch LS the switches are shown only in skeleton form since they do not form a part of the invention and may be of any known type. It is assumed in this case, however, that these switches are of the well known Strowger type controlled over two sides of the line in series by what is commonly known as the two wire method of control. Two subscribers' lines extending from substations T2 and T3 to lineswitches LS and LS1, respectively, are shown. These switches have access to first selectors such as selector S. Selector S1 is an ordinary Strowger type selector and terminates a trunk extending from the operator's position in the third office to the main office. Selector S2, also an ordinary Strowger selector terminates a trunk extending from repeater DR. These switches have access to the local switch train comprising selectors such as S3 and connectors such as C, through which calls are completed to the subscribers in the main exchange. Selector S3 also has access to the trunks extending from the main exchange to the sub-exchange by way of repeaters DR and to trunks extending to the operator's position in the manual office.

In Fig. 6 is shown a link circuit FL comprising a finder switch and a lineswitch, both of which are of the rotary lineswitch type, and associated relays. The finder switch has access in its banks to intercepting trunks extending from repeaters such as repeater DR. The lineswitch has access to trunks extending to the operator in the manual exchange.

In Fig. 7, in the left-hand part of the sheet is shown trunk apparatus TA associated with the main office end of a trunk extending to the manual office. This apparatus terminates a trunk from the banks of local selectors in the main office, a trunk accessible to the link circuits such as link FL, and a trunk extending to an incoming selector in the main office. The terminating equipment TM in the main office is equipped with two jacks, J and J', the former for calling and the latter for answering. The operator's position is provided with two types of cords, a dialling cord DC for cooperating with jacks such as J, and an answering cord AC for cooperating with jacks such as J'.

To set up a connection in the sub-exchange, the calling subscriber first dials two digits whereupon switching repeater SR functions and causes lineswitch DLS to hunt for and connect with an idle local connector such as LC. The next two digits operate this connector in the usual way to extend the connection to the calling line. The first two digits, in addition to operating switching mechanism in the repeater SR also operate apparatus in the main exchange. If the call is from a non-restricted line the first digit causes the selector S2 to raise its wipers to the called level and select an idle trunk, such as the trunk to selector S3. The second digit then operates selector S3, which also raises its wipers to the called level, but immediately on the call being identified as a local one, the switches in the main exchange are released and restore to normal. If the call is for a subscriber in the main exchange, selector S3 hunts for and connects with an idle connector in the called group and that connector, such as connector C, operates in response to the last two digits of the called number to extend the connection to the called line and signal that line in the usual way. If the calling station in the sub-office is restricted to local calls therein, repeater DR does not extend the connection to the incoming selector, but in response to the first two digits switches over and initiates the operation of the link circuit FL. Thus, if the first two digits identify the call as a local one, the trunk is released and the link circuit does not operate. However, if the number called is that of a subscriber at the main exchange the finder switch associated with the link FL connects with the trunk by way of repeater DR and selects an idle operator's trunk such as the trunk TA extending to the operator's position TM. The remaining digits have no effect. The operator then answers the call and on determining the number of the subscriber wanted, dials back over the trunk to operate selector S2 and other switches in the main exchange to set up a connection with the wanted line. The operator then causes the repeater DR to switch over the connec-

tion directly from the trunk to the incoming selectors.

In case a non-restricted line of the sub-exchange or a subscriber in the main exchange desires to call the operator, the selector, such as S3 is operated to the tenth level, whereby the call is extended directly to the operator by way of trunks such as trunk TA and position equipment, such as TM. The operator may also extend calls from either sub- or main exchanges to subscribers in some distant exchange by means of the answering cord circuit and the usual toll line equipment. The operator may also extend incoming calls to subscribers in the sub-exchange by way of trunks, such as trunk TA and selectors such as S1 and S3. In this case, selector S1 is dialled to a local level, such as the eighth level, where an idle selector such as S3 is connected with. Selector S3 is then operated to the tenth level where it hunts for and connects with an idle trunk extending to the sub-exchange. On incoming calls connector IC operates and disconnects itself from the local trunk accessible to the lineswitch DLS. The next two digits of the called number operate the incoming connector in the usual way to establish the connection with the called line. On calls to a main exchange subscriber, selector S3 is operated to a local level and the call completed by way of a connector such as connector C.

Having explained the objects of the invention and the apparatus employed, the operations involved in setting up various connections in a system embodying the invention will now be described in detail.

It will be assumed first that a subscriber at substation T in the sub-exchange is calling a subscriber at substation T3 in the main exchange and that the calling line is a non-restricted line. When a line is non-restricted, terminals 36 and 37 are connected by means of jumper 35, thereby placing a ground on contacts such as contact 57 in the banks of the finder switches which contacts are individual to the respective lines. On lifting the receiver at the substation, a circuit is closed which may be traced from battery, winding of relay 12, armature 19, conductor 2, through the loop at the calling substation, conductor 3, armature 17 to ground. Relay 12 operates and at armature 20 marks the line as calling in the banks of the finder switches by disconnecting ground from the test conductor 33 and connecting that conductor to battery through the winding of relay 11. At armature 21 a circuit is closed for relay 13 of the common starting equipment. Relay 13 operates and at armature 22 closes a point in the circuit over which relay 15 will subsequently operate and relay 14 subsequently release. At armature 23 a circuit is closed for relay 14, and at armature 24 ground is connected to the com-

mon starting lead 177, extending to repeaters such as repeater SR. Relay 14 operates and at armature 25 closes a part of the operating circuit for relay 15; this latter relay does not operate at this time, however, since its winding is shunted out by the ground through armature 23. Ground on the common starting lead, by way of contacts controlled by armature 135 causes the operation 5 of relay 102. Relay 102 closes a circuit at armature 127 for relay 101 and stepping magnet 63 in series; at armature 126 test wiper 53 by way of test conductor 61 is connected at a point between relay 101 and 10 the stepping magnet; at armature 128 a locking circuit is closed for relay 102, including armatures 138 and 162; and at armature 129 a point in the discriminating circuit is closed. In case the test wiper of the finder switch 15 is standing on a contact of a line that is not calling, the wiper will encounter a ground by way of a test conductor, such as conductor 33 and the normal ground connection thereto. This ground will cause the 20 stepping magnet 63 to operate and at the same time shunt out relay 101. Magnet 63, on operating, opens its own circuit at interrupter spring 64 and on deenergizing steps the wipers 51-54 ahead to the next set of 25 contacts. As long as grounded test contacts are engaged the stepping operation is repeated until wiper 53 encounters the contact marked as calling, at which time battery through a cut-off relay, such as relay 30 11 will be encountered and the short circuit removed from relay 101. Relay 101 and the relay such as relay 11 will operate in series from ground on armature 127. Magnet 63, however, will not operate in series with 35 relay 101. Relay 101 then switches the test conductor 61 from the circuit including relay 101 and connects a ground thereto to hold relay 11 in operated position. At armatures 120 and 125 the talking conductors of 40 the trunk are closed through to line relay 103. At armature 123 the discriminating lead is connected up, and at armature 124 the timing device TD is connected through to relay 108. Relay 11, on operating, disconnects the normal battery and ground connection from the calling line at armatures 17 45 and 19, respectively, and at armature 18 connects itself directly to test conductor 33. Ground from the finder switch by way of the test wiper and test conductor now holds 50 relay 11 operated and also marks the line as busy in the connector banks by maintaining a ground on conductor 4. Relay 12 on being disconnected from the calling loop deenergizes and at armature 21 opens the circuit of relay 13. Relay 13 deenergizes, opens the original energizing circuit of relay 14 at armature 23, and at armature 24 disconnects the ground from the common starting conductor. Relay 14 now remains energized in 55 series with relay 15 which also energizes and prepares various circuits which will be described in detail hereinafter. Relay 103 operates over the loop circuit previously traced and at armature 130 closes a circuit for relays 104 and 105 in series. At armature 131 a point in the loop circuit to the switch ahead is closed. Relay 104 operates over the above-traced circuit, and at armature 132 connects ground to the release trunk conductor to hold up relay 101 after relay 102 releases. This ground also extends by way of armatures 156 and 158 and conductor 174 to lineswitch DLS. At armature 133 a point in the local impulsive circuit is 60 closed; at armature 134 an operating circuit is closed for relay 105 independent of armature 130. The function of this latter circuit will be described in more detail later on. At armature 135 the initial energizing 65 circuit of relay 102 is opened and the common starting conductor 177 is switched through to the next repeater of the group, namely repeater SR'. The ground by way of armature 158 and conductor 174 causes 70 the operation of relay 202. Relay 202 and also relay 201 are two-step relays and operate only in their first step initially, closing the contacts marked with the Roman numeral I and under certain conditions operate in their 75 second step and close the additional contacts marked II. If the wipers of the lineswitch are standing on contacts associated with an idle local trunk, nothing happens when relay 202 operates, as above, but if the wipers are standing on contacts associated with an outgoing trunk the operation of relay 202 closes a circuit for the stepping magnet which may be traced from ground on bank contacts associated with the trunk, 80 wiper 224, armature 214 and its resting contact, armature 213 and its working contact, interrupter springs 269, winding of the stepping magnet 203 to battery. The stepping magnet energizes over this circuit and steps 85 the wipers to the next set of contacts. Relay 113 will now operate from ground on the release trunk by way of armature 132, armature 152, winding of relay 113, resistance 119 to battery. This relay is made slow to operate in order that a preliminary ground impulse may be transmitted over conductor 174 on the seizure of the switch. The purpose of this ground impulse is to provide for 90 stepping the lineswitch ahead on each call so that in case of trouble on a trunk a subsequent call on the same line will not be held up indefinitely. Relay 113 on operating 95 closes a point in the loop circuit to the switch ahead at armature 157, at armature 158 disconnects the release trunk from lead 174 and connects it to lead 173, at armature 159 closes a path around armature 156, and at armature 161 closes a point in its own releasing circuit. On ground being removed 100 105 110 115 120 125 130

from conductor 174, relay 202 deenergizes, leaving the wipers of the lineswitch standing on contacts associated with a local trunk. Ground on conductor 173 now causes relay 5 201 to operate in its first step. In operating in its first step, relay 201 actuates armatures 219 and 270 but not the other armatures. A circuit is closed thereby from ground on the test contact corresponding to the local 10 trunk, wiper 221, armature 218 and its resting contact, armature 219 and its working contact, armature 213 and its resting contact, interrupter springs 269, stepping magnet 203 to battery. The stepping magnet 15 operates over the above circuit and at armature 269 interrupts its own circuit, and, on deenergizing, steps the wipers 221—225 ahead to the next set of contacts. If the next set of contacts is engaged, the test contact such 20 as contact 232 will be grounded, thereby causing the reoperation of the stepping magnet which again steps the wipers ahead to the next set of contacts. The hunting operation continues until the test wiper encounters 25 the contacts associated with an idle trunk, such as the trunk comprising conductors 233—235. It will be noted that all contacts corresponding to local trunks with which wiper 221 engages, and contacts correspond- 30 ing to outgoing trunks with which wiper 224 energizes are permanently grounded. Wiper 221 not encountering ground, relay 201 will operate in its second step from ground on conductor 173, upper winding of relay 201, 35 armature 270, armature 219, armature 213 and its resting contact, interrupter springs 269, winding of magnet 203 to battery. The stepping magnet 203, however, will not operate in series with the upper winding of 40 relay 210. At armatures 217 and 220 the talking conductors of the trunk are switched through to the wipers, and at armature 218 a ground is placed on the release trunk conductor extending through wiper 221, bank 45 contact 232, conductor 234, armature 321, contacts controlled by armature 357, relay 301, to battery. Relay 301 operates and at armatures 314 and 315 disconnects the talking conductors of the trunk from the incom- 50 ing connector IC and switches them over to the talking conductors of the trunk leading to the main exchange. A loop circuit has now been extended to the repeater, such as DR, in the main exchange responsive to the 55 lifting of the receiver at the calling station. This circuit may be traced as follows: battery, upper winding of relay 406, upper winding of relay 405, armatures 422, 418, and 414, conductors 452, 450, and 352, armature 314 and its working contact, conductor 233, contact 230, wiper 222, armature 217, conductor 171, armature 131, winding of relay 114, armature 157, contacts controlled by armature 136, armature 155, conductor 60 175, armature 220, wiper 223, contact 231, conductor 235, armature 315, conductors 353, 449, and 451, armatures 415, 420, and 424, lower winding of relay 405, lower winding of relay 406, contacts controlled by armature 441, contacts controlled by armature 445, to ground by way of the induction coil DT' on which a dial tone is superimposed. The dial tone informs the calling subscriber that the trunk has been seized and that dialling may commence. Relay 114 operates in the above loop circuit and at armature 163 connects the discriminating lead to the positive trunk conductor 175, thereby shunting out the lower winding of relay 406 and unbalancing relay 405. Relay 405 is so constructed that its two windings oppose each other and prevent it from actuating its armatures when normally connected. When unbalanced by the ground on the positive side of the line 70 relay 405 operates. Relay 114 also opens the circuit of relay 102 at armature 162, the latter relay deenergizes after a short interval and disconnects the discriminating lead from the trunk. Relay 102 opens the initial energizing circuit of relay 101 at armature 127; relay 101 now holding up from ground by way of armature 132 and armature 122. Relay 406, on operating, as previously described, closes an obvious circuit for relay 407 at armature 428. Relay 407 operates 75 and at armature 429 closes a circuit for relay 402, at armature 430 closes a point in the circuit of relay 408, and at armature 431 closes a point in the circuit of relay 403 which will be described subsequently. Relay 405, on operating, completes the circuit of relay 403 by way of armature 427 and armature 431. Relay 403 operates and at armature 417 connects itself to release trunk conductor 448 of selector S2, at armatures 418 and 420 the talking conductors are disconnected from relay 406 and connected to conductors 446 and 447, extending to the line relay of selector S2, at armature 419 an additional ground is placed on the holding circuit for relay 402, 80 and at armature 421 an additional point is closed in the circuit of relay 403. The line relay of selector S2 operates over the previously traced loop circuit and the release relay which also operates in the usual way returns ground over release trunk conductor 448 to hold relay 403 in operated position. The selector also places a dial tone on the line in the usual manner to replace the dial tone originally supplied by repeater DR. 85 Relays 405, 406, 407, deenergize and open the circuits previously closed by their respective operations, but this has no effect at this time. Relay 402, on operating, at armature 416 disconnects relay 401 from the release trunk conductor and connects the ground to that conductor to mark the trunk busy in the banks of the local selectors. The calling line has now been extended by way of repeater SR, lineswitch DLS, and repeater DR 90 95 100 105 110 115 120 125 130

to incoming selector S2 in the main exchange.

At this point the further operation of the apparatus depends on whether or not the calling subscriber dials within a certain predetermined time interval. A timing device or interrupter TD arranged to connect ground to a timing conductor at certain predetermined intervals is associated with repeater SR. This device may be common to a number of repeaters and may be so arranged that the timing operation is started responsive to the seizure of the associated switch, or if exact timing is not required, it may be arranged to operate continuously and ground the timing conductor at regular intervals. The interval allowed before starting to dial will depend on local conditions and may be any reasonable interval for instance, from one and one-half to three minutes. It will be assumed in this case that the allowed interval is three minutes and that the timing device TD is adapted to start operating responsive to the seizing of repeater SR and to place ground impulses on the timing conductor at one and one-half minute intervals thereafter.

In case the calling subscriber dials before the first ground impulse is transmitted the disconnect circuit does not function, since the timing conductor is opened at one or more points by armature 143, 147 or 150. However, if the calling subscriber does not dial within this interval, a circuit is closed from ground, timing device TD, armatures 124, 150, 147 and 143, winding of relay 108 to battery. Relay 108 operates and at armature 144 closes a holding circuit for itself in series with relay 107 to ground at armature 132. Relay 107 does not operate at this time as its winding is shunted by the ground on the timing conductor. When ground is removed from the timing conductor at the end of the impulse, relay 107 operates and at armature 142 closes a point in the circuit of relay 112, and at armature 143 switches the timing conductor from relay 108 to the circuit of relay 112.

If the subscriber now dials before the second timing impulse is received, the timing conductor will be opened at armature 147 or 150 as will be described in detail hereinafter, and relay 112 consequently will not operate. Relays 107 and 108 will remain energized but will have no effect on the connection. Assuming that the subscriber does not dial within the allowed interval, the second timing impulse will cause relay 112 to operate. The previously traced loop circuit to the main office is then opened at armature 155 and a busy tone from the tone generator BT is connected to the upper talking conductor of the calling trunk. At armature 156 and contacts controlled thereby, the release trunk conductor is disconnected from conductor 173, the timing conductor is disconnected from relay 112, and a holding circuit for that relay is

closed including the release trunk conductor and ground at armature 132. Opening the loop allows the switches in main office to release and the removal of ground from conductor 173 permits the release of lineswitch DLS, of which a more detailed description will be given later. The busy tone on the line will inform the subscriber that it is necessary to hang up the receiver before attempting to dial.

To proceed with the call in the event that the subscriber dials within the allowed interval it will be assumed that the wanted subscriber is assigned the number 8395. The calling subscriber now operates the calling device or dial in accordance with the first digit of the called number, and the calling loop is interrupted as is well known in the art. As relay 103 responds to the first digit, the circuit of relay 104 is momentarily opened and closed at armature 130. Each time the circuit of relay 104 is opened its winding is short circuited at contacts controlled by armature 130, thus rendering the relay slow to release. The short circuit of the winding of relay 104 permits relay 105 to operate from ground at armature 134. Relay 105 is also slow to deenergize since each time its operating circuit is opened, a high resistance circuit through relay 104 is closed. These two relays, therefore, remain operated during the series of impulses. At armature 136 and contacts controlled thereby relay 114 is cut out of the loop circuit extending to the main office and a new loop circuit is closed to improve the impulsing over the trunk. Relay 114 deenergizes but this has no effect at this time.

As armature 130 drops back in response to the first impulse, a circuit is closed from ground, armature 130 and its resting contact, armature 133, armature 146 and thence by one branch connection through the winding of stepping magnet 116 to battery, and by way of the other branch and contacts controlled by armature 140 through the winding of relay 106 to battery. Relay 106 operates and at armature 139 closes an additional point in the impulsing circuit independent of armature 146, at armature 140 and contacts controlled thereby disconnects itself from the impulsing conductor and closes a locking circuit for itself to ground at armature 137, and at armature 141 disconnects ground from wiper 165. Stepping magnet 116 energizes and deenergizes responsive to each impulse and steps the wiper ahead to the contact corresponding to the digit dialled. As the wipers leave their normal or home position off-normal contacts 164 close and relay 109 operates over an obvious circuit. Relay 109 on operating, at armature 145, closes a point in the circuit of release magnet 115, at armature 146 opens a point in the impulsing circuit which, however, is now closed at arma-

ture 139, at armature 182 closes a point in the circuit over which relay 110 will subsequently hold, at armature 147 opens a point in the previously described timing circuit, 5 and at armature 179 disconnects conductor 181 from the dial tone generator DT and connects it instead to the busy tone machine BT. Since the first digit dialled consists of eight impulses, wiper 165 will be advanced 10 eight steps to contact 166.

Shortly after the last impulse of the series, relay 105 deenergizes and at armature 136 and contacts controlled thereby reestablishes the 15 original loop circuit including relay 114, and opens the locking circuit for relay 106 at armature 137. Relay 106 deenergizes, opens the auxiliary impulsing circuit at armature 139, at armature 140 and contacts controlled thereby opens a point in its own locking circuit and again connects its winding to the 20 impulsing circuit, and at armature 141 closes a circuit from ground, armature 141, wiper 165, contact 166, contacts controlled by armature 149, winding of relay 110 to battery. Relay 110 operates and at armature 148 closes 25 a circuit for release magnet 115 including armatures 151 and 145, at armature 149 and contacts controlled thereby disconnects itself from its operating circuit via contact 166 and 30 closes a locking circuit for itself to ground by way of armatures 153 and 182 and in parallel therewith through the winding of relay 111 to ground at armature 132. Relay 111 does not operate at this time since its 35 winding is shunted by the ground at armature 182. Release magnet 115 operates and restores wiper 165 to its normal or home position whereupon contacts 164 separate and open the circuit of relay 109. Relay 109 de- 40 energizes, opens a point in the release magnet circuit, closes the original impulsing circuit, and by retracting its armature 182 removes the shunt from relay 111. Relay 110 now remains locked up in series with relay 111 45 and the latter relay also operates. Relay 111 on operating opens a point in the circuit of release magnet 115 at armature 151, at armature 152 opens one of the parallel paths over which relay 113 and the line-switch DLS 50 are held operated, at armature 153 opens a point in the shunt circuit for its own winding so that the subsequent operation of relay 109 will have no effect, and at armature 154 closes a point in a shunt circuit for relay 55 113 which is without effect at this time.

Should the first digit be any other than the digit 8, the operation will be the same in general except that no circuit will be closed for relay 110 and consequently neither relay 110 60 nor relay 111 will operate. No circuit will be closed at this time for release magnet 115 and wiper 165 will remain on the contact on which it was set until the connection is released. Relay 109 will remain operated and maintain the impulsing circuit open so that

subsequent impulses will have no effect at the repeater. The above also applies when the first digit is a 4, this being without effect due to the open circuit at armature 154. The operation of the equipment in the main office 70 is not affected.

Each deenergization of relay 103 as it follows the dialled impulses opens the loop circuit to the main office at armature 131. These interruptions cause the line relay of selector 75 S_2 to operate in the usual way and the selector raises its wipers opposite the eighth level and then selects an idle trunk in that level. It will be assumed that the trunk selected is the one comprising conductors 528—530 terminating in contacts 525"—527" and extending to selector S_8 . 80

The first digit has now been dialled with the result that relays 110 and 111 of repeater SR are locked in operated position and selector S_2 at the main exchange has extended the loop circuit to the line relay of selector S_8 . The apparatus is now in condition to receive the next series of impulses corresponding to the second digit of the called number, 90 that is, the digit 3. Relay 103 responds to the impulses and relays 105, 106, 109 and stepping magnet 116 operate as in the previous case. Wiper 165 is stepped to the third contact which is left dead since it corresponds to a 95 main office number. The loop to the main office is interrupted at armature 131 and the line relay of selector S_8 responds in the usual way to cause the selector to advance its wipers opposite the third level. The selector then rotates automatically until its wipers 531—533 are set on an idle trunk which will be assumed to be the trunk extending from contacts 534—536 to connector C. Returning 100 now to repeater SR, shortly after the last impulse of the series, relays 105 and 106 de-energize as before but as wiper 165 is standing on a dead contact, no circuit is closed. Relay 109 remains operated during the remainder of the connection and at armature 146 maintains the local impulsing circuit open so that the subsequent digits have effect at the repeater. 105

Relay 103 responds to the next two digits 110 and repeats them over the loop to the line relay of connector C which responds in the usual way. Assuming that these digits are 9 and 5, respectively, wipers 537—539 are stepped to contacts 540—542 associated with the line terminating at substation 8395. In case the line is busy in another connection, the connector will return the busy tone to the calling subscriber in the usual manner whereupon the calling subscriber will hang up and release the connection. If the called line is idle, the connector will switch through in the usual manner, operate the cut-off relay of the lineswitch LS1, and signal the called subscriber in the usual way. The calling subscriber will be given the usual ring- 115 120 125 130

back tone. When the called subscriber answers the conversation may take place, the connector feeding talking battery to the called line through the back-bridge relay and to the trunk through the line relay. Battery for the calling line is fed through line relay 103 of repeater SR. The calling line and trunk are inductively connected through condensers 117 and 118 through which the voice currents pass.

When through talking, both subscribers hang up their receivers. Hanging up by the called subscriber has no effect except to de-energize the back-bridge relay of the connector. When the calling subscriber hangs up, the loop over which relay 103 is held operated is opened and that relay deenergizes. Shortly after this, relay 104 deenergizes and disconnects ground from the release trunk at armature 132. Relay 105 energizes momentarily but without effect. Relay 103 on de-energizing opens the loop to the main office and the connector deenergizes in the usual manner, removing ground from the release trunk to permit the release of selectors S_2 and S_3 as well as relay 403 of repeater DR. Ground being removed from the release trunk of repeater SR, relay 201 of lineswitch DLS restores to normal as do relays 11, 101, 111 and 113. Relay 109 remains operated from ground on the off-normal contacts 164 and, on relay 111 deenergizing, a circuit is completed for release magnet 115 which restores wiper 165 to normal position. The circuit of relay 109 is then opened at the off-normal springs and that relay restores. The apparatus is now in normal position and ready to receive the next call.

Consider now a connection between substations T and T, as above described in which the calling substation is restricted to local calls in the sub-exchange. In this case there will be no connection between terminals 36 and 37, hence the discriminating conductor 34 will not be grounded. The calling subscriber on lifting the receiver is connected with repeater SR by way of finder switch F, and a loop is extended to an incoming repeater DR in the main office by way of a lineswitch DLS exactly as described in the previous connection. However, since no ground is present on the discriminating conductor which is connected to the line on the operation of relay 114, differential relay 405 of repeater DR will not operate as in the previous case. Since relay 405 does not operate, the circuit of relay 403 will remain open and the loop will, therefore, not be switched over to incoming selector S_2 . Relays 406, 407 and 402 will operate as previously described and the calling subscriber will receive the dial tone by way of induction coil DT'. The apparatus is now in condition to receive the dialled impulses.

It will be remembered that the number 8395

is assigned to substation T, which number the calling subscriber now dials.

Relay 103 responds to the impulses of the first digit and repeater SR functions exactly as described in the previous connection. Relay 103 interrupts the loop circuit extending to repeater DR and relay 406 which is energized over the loop responds to these interruptions. As relay 406 responds to the impulses, the circuit of relay 407 is momentarily opened and that of relay 408 is momentarily closed at armature 428 at each impulse. Relay 408 energizes and remains operated during the series of impulses due to its slow releasing characteristic. Relay 407 also remains energized during impulsion when its circuit is momentarily opened at each impulse. Relay 408 on operating opens a point in the starting circuit at armature 432 and closes a circuit from ground, armatures 438, 433 and 439, relay 412 to battery. Relay 412 operates and opens a point in the circuit of relay 410 at armature 442, opens another point in the starting circuit at armature 443, closes a circuit for itself and relay 411 in series at armature 444 and at armature 445 disconnects dial tone ground from the lower winding of relay 406 and substitutes an ordinary ground. Relay 411 does not operate at this time since its winding is shunted by the ground on armature 438. Shortly after the last impulse of the series, the previously described operations take place in repeater SR and relay 408 of repeater DR also deenergizes. Relay 408 on deenergizing removes the shunt from relay 411 and that relay operates in series with relay 412. Relay 411 on energizing closes a point in the circuit of relay 410 at armature 436, closes a point in the starting circuit at armature 437, at armature 438 disconnects the ground from armature 433 and substitutes battery through resistance 413, closes a holding circuit for its own lower winding at armature 440 and at armature 441 connects another ground to the lower winding of relay 406 to prevent a subsequent connection of dial tone ground to that relay. The apparatus is now in condition to receive the next series of impulses.

The calling subscriber now dials the digit 3 and relay 103 of repeater SR responds and repeats the impulses over the loop to relay 406 of repeater DR. Repeater SR functions in exactly the same manner as described in the previous connection. Relay 408 of repeater DR operates as previously and at armature 432 again opens a point in the starting circuit which is also open at armature 442, and at armature 433 closes a circuit from battery, resistance 413, armature 438, armature 433, armature 439 and its working contact (relay 411 having previously operated), upper winding of relay 411 to ground at armature 431. Relay 412 which was held operated in series with the upper winding

of relay 411 is thereby shunted out and de-energizes, closing a point in the circuit of relay 410 at armature 442, closing a point in the starting circuit at armature 443, opening 5 a point in its own holding circuit at armature 444, and switching back the normal dial tone circuit at armature 445. The latter circuit is not effective at this time since it is open at contacts controlled by armature 441. Shortly 10 after the last impulse of the series, repeater SR functions exactly as described in the previous connection and relay 408 deenergizes as previously. Relay 408 on deenergizing at this time closes a circuit from ground, armatures 423, 432, 443, 437, 436 and 442, winding of relay 410 to battery, and in parallel thereto, conductor 454, contacts controlled respectively by armatures 636 and 622, winding of relay 603 to battery. Relay 410 operates 15 over the above circuit and at armature 455 closes a locking circuit for itself independent of armature 432, and at armature 435 switches the guarding conductor 453 from ground at armature 425 to battery through 20 the winding of relay 404 to mark the trunk as calling in the banks of the finder switches of links FL. Proceeding now to the link FL, relay 603 energizes in parallel with relay 410 over the previously traced circuit. On operating, relay 603 closes a circuit for relay 602 and stepping magnet 663 in series at armature 628, and at armature 627 connects test wiper 655 between relay 602 and magnet 663. Contacts with which wiper 655 engages are 25 grounded by way of guarding conductors such as conductor 453 for all trunks except those on which calls are being extended as just described, in which case the test contact will be marked by battery through a cut-off 30 relay such as relay 404. As long as wiper 655 encounters grounded contacts relay 602 will be shunted out and magnet 663 will energize from ground on the test contact, armatures 618, 625, and 627, interrupter springs 40 664, stepping magnet 663 to battery. The stepping magnet on energizing opens its own circuit at interrupter springs 664 and on de-energizing steps wipers 658—657 ahead to the next set of contacts. This operation is the 45 same as previously described for finder switch F and is repeated as long as wiper 655 engages a grounded contact. When the wiper engages the contact marked as calling, the shunt is removed from relay 602 and 50 that relay operates over the previously traced circuit in series with the stepping magnet. The stepping magnet does not operate, however, due to the high resistance of relay 602. Relay 602 switches the test wiper from its 55 previous connection between relay 602 and the stepping magnet to the opposite side of relay 602 at armature 625, switches the operating conductors through at armatures 619 and 620, connects ground to the local release 60 trunk lead at armature 621, disconnects the 65 starting lead from relay 603 at armature 622 and switches it to the next finder link circuit by way of conductor 665, closes a holding circuit for relay 603 at armature 623, closes a point in the circuit of relay 613 at armature 624, and switches the talking conductors 70 through at armatures 626 and 675. To return now to repeater DR, the operation of the switching relay of the link circuit closed a circuit from ground armatures 628, 625 and 618, wiper 655, contact 660, conductor 453, contacts controlled by armature 426, armature 435, winding of relay 404 to battery. Relay 404 operates, disconnects the calling loop from line relay 406 at armatures 422 and 424, 75 closes an additional circuit for relay 402 and opens the circuit of relay 410 at armature 423, closes a circuit for relay 409 at armature 425 and at armature 426 connects itself directly to the guarding conductor independent of 80 armature 435 of relay 410. Relays 406, 407, 410 and 411 now deenergize but have no further effect on the connection. Relay 409 energizes and at armature 434 closes a point in the circuit of relay 403 which, however, is now 85 open at armature 425. The calling loop is now extended by way of conductors 352 and 353, contacts 661 and 662, wipers 656 and 657, armatures 626 and 675, left-hand windings of 90 repeating coil R, upper and lower windings of impedance coil 616 to battery and ground, respectively. Further dialling by the calling subscriber will have no effect either before or after the operation of relay 404. 95

The operations of relays 602 and 603 and stepping magnet 663 have been described. The finder switch has extended the calling trunk to the link FL whose operation will now be considered. The operation of relay 602 closed a circuit from ground, armature 100 621, armature 635, relay 606 to battery, and in parallel thereto, through armature 640, relay 611 to battery. Relay 606 operates and at armature 632 closes a locking circuit for 105 itself including contacts controlled by armature 630, closes an obvious circuit for relay 604 at armature 633, and connects up a signalling circuit at armature 634 which will be described in detail hereinafter. Relay 611 also operates and at armature 641 closes a 110 point in the circuit of relay 612 which has no effect at this time. Relay 604 operates, closes a point in its own circuit which will be effective at a later stage of the operation and closes a loop circuit for selector S2 at armature 115 676. Relay 602 also closed a circuit from supervisory ground, armatures 624 and 649, relay 613 to battery. Relay 613 operates and at armatures 645 and 646 completes a hunting 120 circuit similar to the previously described circuit of the finder switch. If the wipers 666—668 are standing on contacts associated with a busy trunk, test wiper 666 will encounter a ground and stepping magnet 615 will 125 operate in the well known manner to advance 130

the wipers to the next set of contacts. This operation is repeated until an idle trunk is found whereon relay 614 operates in series with the stepping magnet, switches the test wiper over to its upper terminal, at armature 648, closes a holding circuit for itself at armature 647, opens the circuit of relay 613 at armature 649, and at armatures 650 and 651 switches through a simplex signalling and talking circuit which will be considered in detail later on. Relay 602 also prepares an operating circuit for the incoming selector S2.

Considering now the trunk circuit TA, the operation of relay 614 (of link FL) closed a circuit from ground, armatures 621, 647, and 648, wiper 666, contact 669, conductor 672, armature 727, relay 701 to battery. Relay 701 energizes and at armatures 720 and 721 connects the trunk circuit through to operator's equipment TM in the manual exchange. A circuit may now be traced from battery, armature 634, relays 608 and 609 in series, right-hand windings of repeating coil R, thence in two parallel paths by way of armatures 643 and 644 and their respective resting contacts, armatures 650 and 651, wipers 667 and 668, contacts 670 and 671, conductors 673 and 674, armatures 720 and 721 and their respective working contacts, trunk conductors 757 and 758, left-hand windings of repeating coil R4, conductor 750, contacts controlled respectively by armatures 744 and 745, relay 712 to ground at armature 740. Relays 608, 609 and 712 operate over the above circuit. Relay 608 opens a point in the circuit of relay 605 and closes a circuit for relay 607 at armature 638. Relay 609 opens a point in the circuit of relay 601 at armature 639. Relay 712 closes a circuit for the line lamp L1 at armature 743. Relay 607 operates and at armature 635 opens the original energizing circuit of relay 606, which, however, remains operated over a circuit including armature 632 and contacts controlled by armature 630. Relay 607 also closes another circuit at armature 636 for switching the starting conductor through to the next switch, and at armature 637 closes a point in the circuit of relay 605. Lamp L1 lights to notify the operator that a call is awaiting attention.

To answer the call, the operator inserts the plug of cord AC into jack J', closing a circuit for relay 711 by way of the sleeve of the plug, and bridging the left-hand windings of repeating coil R5 across the trunk section inductively coupled to the trunk by way of repeating coil R4. Relay 711 energizes and at armature 740 disconnects ground from the trunk and substitutes battery therefor, opens the circuit of lamp L1 and closes a circuit for lamp L2 at armature 741. Lamp L2 lights indicating that the call is from a restricted line. Relays 608, 609 and 712 de-

65 energize when battery is connected to the

manual end of the trunk. Relay 608 on de-energizing closes a circuit for relay 605 at armature 638. The circuit of relay 607 is opened but due to its slow releasing characteristic, that relay maintains its armatures 70 in actuated position during the short interval of open circuit. Relay 605 energizes and at armature 630 and contacts controlled thereby opens the holding circuit of relay 606 and completes a circuit for relay 604 independent of armature 633. Relay 606 de-energizes and opens a point in its own holding circuit at armature 632, opens the circuit of relay 604 at armature 633 and at armature 634, disconnects battery from the trunk 80 and substitutes the normal ground connection. Relays 608, 609 and 712 again operate over the previously traced simplex circuit from ground at the main office to battery at the manual office. Relays 609 and 712 were without effect on their momentary deenergization. Relay 608 on energizing again opens the circuit of relay 605 and closes the circuit of relay 607 which has not yet deenergized. A short time after its circuit 90 is opened, relay 605 which is a slow-acting relay deenergizes and at armature 630 opens the holding circuit of relay 604. Relay 604 deenergizes and at armature 676 opens the first loop circuit to the selector in the main office, the loop now being extended through armature 677 and right-hand windings of repeating coil R1. Relay 604 also prepares a circuit for relay 612 at armature 629.

The connection has now been extended to the operator at the manual exchange. The talking circuit comprises five inductively coupled sections as follows: First, the loop circuit extending from the calling substation to repeater SR to which battery and ground 100 are fed through relay 103. Second, the loop circuit extending from repeater SR by way of lineswitch DLS, connector IC, the trunk 105 extending from the sub-office to the main office, repeater DR, link FL to the left hand winding of repeating coil R. Battery and ground are fed to this loop through impedance coil 616. Third, the simplex circuit extending from the right hand windings of repeating coil R, the trunk extending from the main office to the manual office, to the left hand windings of repeating coil R4. Battery and ground from the main office. Fourth, the dry-loop circuit extending from 110 the right hand windings of repeating coil R4 through the operator's answering jack to the left hand windings of repeating coil R5 of the answering cord. Fifth, the loop extending from the right hand windings of repeating coil R5 to the operator's telephone set which may be of any known type. These sections are all inductively coupled, the first and second through condensers 117 and 118, the second and third through repeat- 115

120

125

130

ing coil R, the third and fourth through repeating coil R4 and the fourth and fifth through repeating coil R5. The operator talks with the calling subscriber and determines the identity of that subscriber and also the number of the wanted subscriber. The calling subscriber is then instructed to wait on the line while the operator completes the call. The operator makes out the usual toll ticket so that the proper charge may be made for the call.

As previously mentioned, on the seizure of the link FL, a loop circuit is extended to the incoming selector S2 at the main exchange and when the call is answered, the loop is placed under the control of the operator. This circuit may be traced from battery and ground through the line relay (not shown) of selector S2, conductors 446 and 447, contacts 658 and 659, wipers 653 and 654, armatures 619 and 620, armature 677, and right-hand windings of repeating coil R1. The line relay of the selector operates over the above circuit in the usual way. It will be noted that the primary windings of the repeating coil are normally short circuited by armatures 643 and 644. This feature will be explained more in detail hereinafter.

The operator having determined the number of the wanted subscriber, now inserts the plug of dialling cord DC in jack J and dials the complete number. When the dial is turned off-normal, a circuit is closed from battery, contacts 754 of the off-normal springs, over the ring contact of the plug, relay 713 to ground. Relay 713 operates and at armature 744 and contacts controlled thereby, disconnects battery through relay 712 from the trunk and substitutes battery through impulsive contacts 756 of the dial and the tip of the plug. As the dial returns to normal, the impulsive springs open the circuit in accordance with the particular digit dialled. Relays 608 and 609 respond to these interruptions by deenergizing and reenergizing. Relays 608 in deenergizing responsive to the first impulse closes a circuit for relay 605 as previously described. Relay 605 energizes and at armature 630 closes a circuit for relay 612. Relay 612 energizes, closes a locking circuit for itself at armature 642 and at armatures 643 and 644 removes the short circuit from the left-hand windings of repeating coil R1 and short circuits the right hand windings of repeating coil R. The left-hand windings of repeating coil R1 are now included in the impulsive circuit. With each deenergization, relay 608 also opens the loop circuit to selector S2 at armature 677. Selector S2 operates in the usual way to step its wipers to the called level and then select an idle trunk. The three remaining digits are dialled and are repeated in the same manner, operating a selector such as selector S3 and a connector such as connector C. Relay 605

energizes during impulsive and remains operated throughout each series of impulses. It has no further functions however, after closing the circuit of relay 612 except to open the circuit of AC relay 610 to guard against that relay's operating due to the dialling impulses. The calling subscriber does not receive objectionable clicks when the loop to the selector is interrupted due to the short circuit around the windings of repeating coil R. The dial on returning to its normal position opens the circuit of relay 713 which deenergizes and restores the trunk to its previous condition with relay 712 in the circuit.

The connector, having been set on the contacts of the wanted line, operates in the same manner as in the previously described connection. If the line is busy, the connector places a busy tone on the trunk which is audible to the operator but not to the calling subscriber since repeating coil R is short circuited. The operator then operates key K forward separating contacts 751 and closing contacts 752. Relay 710 operates from ground on contacts 752 and at armature 739 connects alternating current from generator G to the trunk by way of conductor 750. The alternating current circuit extends through relay 610, armature 631, and condenser 678 to ground. Relay 610 energizes and at armature 640 opens the circuit of relay 611. Relay 611 deenergizes shortly afterward and at armature 641 opens a point in the circuit of relay 612 which also deenergizes. Relay 612 opens a point in its own locking circuit at armature 642, and at armatures 643 and 644 again short circuits the windings of repeating coil R1 and removes the short circuit from repeating coil R. The operator is again connected in a talking circuit with the calling subscriber and informs the subscriber that the wanted line is busy. The busy tone from the connector will not be heard at this time by either the operator or subscriber due to the short circuit on repeating coil R1.

If the called subscriber is idle, the connector switches through and signals the called subscriber in the usual manner. The operator will wait until the subscriber answers, thereby verifying the completion of the call and inform the subscriber that a toll call is waiting. The operator then actuates key K to the rear, closing a circuit from battery, contacts 753, sleeve of the plug and jack, relay 714 to ground. Relay 714 energizes and at armature 745 disconnects relay 712 from the trunk and substitutes resistance 759 therefor. Resistance 759 is of such a value that relay 608 will remain operated in series therewith, but relay 609 will release. Relay 609 on falling back closes a circuit from ground, armature 638, armature 639, relay 601 to battery. Relay 601 energizes, opens the circuit of relay 603 at armature 617, and opens the holding circuit of relay 404 of repeater DR

at armature 618. Relay 404 falls back immediately, opens the circuit of relay 409 and closes a circuit for relay 403 including armature 434 and its working contact, relay 409 remaining operated a short time after its circuit is opened due to its slow releasing characteristic. Relay 403 operates and switches the incoming trunk through to selector S_2 as in the previous connection. The connection set up by the operator via selector S_2 is now held up by the calling loop and relay 403 is maintained in operated position by ground on release trunk conductor 448. The relays of repeater DR deenergize as in the previous case. Returning to link circuit FL, relay 602 deenergizes, opens the operating loop to the selector and removes ground from the local release trunk. Relays 611 and 614 deenergize, the latter disconnecting the outgoing trunk. Relays 601, 607, and 608 then deenergize and the link circuit is ready to respond to the next call. Relay 701 deenergizes and transfers the operator's trunk to its normal connection. The operator then withdraws the plugs of cords AC and DC whereon all equipment in the manual office restores to normal.

In case the subscriber in the above described call had dialled the number assigned for calling the operator, that is the digits 80, the connection would be set up exactly as in the previous instance. If the call was for a subscriber in the main office it would be completed as in the previous instance. In the case of a long distance call, the operator being informed that the call is from a restricted line by the lighted condition of lamp L2 after answering the call, can handle the call as required by local conditions. If restricted lines are denied long distance service the operator will so inform the calling subscriber. If long distance calls are allowed, these may be handled in either of two ways; the operator will instruct the subscriber to hang up and will extend another connection over a dialling trunk when the long distance connection has been set up; or the operator will dial back as in the previous connection to extend the call by way of selectors S_2 and S_3 to another trunk to the manual board. The call will be switched over at repeater DR as in the previous case and will thenceforth be handled as a call from a non-restricted subscriber as will be described hereinafter.

A call from a non-restricted line in the sub-exchange to the operator will now be described. It will be assumed that the subscriber at substation T desires a long distance connection and calls the operator by dialling the code number 80. The calling line is extended to repeater SR by finder switch F and to selector S_2 in the main office by way of lineswitch DLS and repeater DR in the same manner as for a call to a main office subscriber. Repeater SR and selectors S_2

and S_3 respond as in the above-mentioned connection. Selector S_3 , however, is operated to the tenth level where it selects an idle trunk such as the trunk comprising conductors 549—551 terminating on contacts 546—548. Selector S_3 on seizing the trunk completes a circuit from ground on the release trunk, through wiper 533, contact 548, conductor 551, contacts controlled by armature 716, relay 709 to battery. Relay 709 energizes and at armature 734 completes two parallel circuits, one for relay 702 by way of armatures 728 and 724, the other for the upper winding of relay 707 in series with resistance 717, and including armature 731. Relay 707 does not operate over its upper winding alone in series with resistance 717. Relay 709 also disconnects the outgoing trunk and connects up the talking conductors of the incoming trunk at armatures 735 and 738, and at armatures 736 and 737 disconnects the lower winding of relay 707 from the bridge across the right-hand windings of repeating coil R3 and substitutes the two windings of relay 705 therefor. Relay 702 energizes, closes a holding circuit for itself at armature 722 independent of armature 728, closes a holding circuit for relay 709 at armature 718, and at armature 723, substitutes battery for the normal ground connection on the trunk extending to the manual office. A circuit may now be traced from battery, armature 723, lower winding of relay 708, contacts controlled by armature 732, conductor 749, thence in two parallel paths by way of left-hand windings of repeating coil R3, armatures 720 and 721, left-hand windings of repeating coil R4, conductor 750, contacts controlled respectively by armatures 744 and 745, relay 712 to ground at armature 740. Relay 708 energizes, closes a circuit for relay 704 at armature 733, and at armature 755 closes the calling loop through to relay 705 by way of the right-hand windings of repeating coil R3 and armatures 736 and 737. Relay 704 energizes, connects a busy ground to release trunk conductor 748 at armature 725, closes a point in the circuit of relay 703 at armature 726, disconnects relay 709 from release trunk conductor 551 and places a holding ground on that conductor at armature 716 and contacts controlled thereby, and at armature 728, opens the original circuit of relay 702 and places an additional holding ground on the local release trunk. Relay 705 operates over the calling loop, closes a point in the circuit of relay 707 at armature 729, and at armature 730 closes an obvious circuit for relay 706. Relay 706 energizes, closes a holding circuit at armature 760 for relay 709 which was held up by ground at armature 718 after being disconnected from conductor 551, and at armature 731 opens the previously traced circuit for the upper winding of relay 707 in series with re-

sistance 717. It has taken considerable time to describe the operations taking place in the trunk apparatus TA subsequent to its seizure by the selector, but it is to be understood that these operations actually take place very rapidly and a holding ground is returned over the release trunk before the release relay of the selector has time to fall back. The selector and preceding switches are now maintained in operated position by this holding ground from the trunk apparatus. Relay 712 of the incoming trunk LC has operated as in the previously described connection and line lamp L1 lights to inform the operator that a call is awaiting attention.

The operator now inserts the plug of answering cord AC in jack J', operating relay 711 as in the previous connection. Relay 711 substitutes battery for the normal ground connection on the trunk at armature 740. Relays 708 and 712 momentarily deenergize. Relay 708 on falling back momentarily opens the circuit of relay 704 and closes a circuit for relay 703, armature 726 being actuated. The calling loop is also momentarily opened at armature 755. Relay 705 also deenergizes momentarily but this is without effect at this time. Relay 704 does not deenergize immediately due to its slow releasing characteristic. Relay 703 energizes and opens the holding circuit of relay 702 at armature 724. Relay 703 is also slow to release, and maintains its armature actuated long enough to insure the release of relay 702. Relay 702 on deenergizing again connects a ground to the trunk at armature 723 and relays 708 and 712 again operate. Relay 708 again closes the circuit of relay 704 which has not deenergized and closes the calling loop through to relay 705. Relay 705 again operates and completes a circuit for the upper winding of relay 707 by way of armatures 729 and 718. Relay 707 operates over this circuit and at armature 732 and contacts controlled thereby, connects the upper and lower windings of relay 708 in series in the trunk. The upper winding of relay 708 is of relatively high resistance and the current flow over the trunk is reduced so that relay 712 deenergizes. The interval during which relay 712 is energized after the insertion of the operator's answering plug is too short to permit lamp L₂ to light, and the circuit of the lamp is again opened when relay 712 falls back. The failure of lamp L₂ to light informs the operator that the call is from a non-restricted line. The operator is now connected with the calling subscriber by way of repeating coils R3, R4 and R5.

Such calls to the operator will usually be made when a long distance connection is required. The operator may complete the call while the subscriber waits on the line or may request the subscriber to hang up and wait until the operator calls back. Assuming that the call is to a near-by town and can be com-

pleted without undue delay, the operator will simply extend the call by way of the answering cord AC in the usual manner in which toll calls are set up. Answering supervision will be provided by the cord circuit in known manner. When the conversation is completed and the calling subscriber hangs up, the calling loop will be opened at the switching repeater in the sub-office, and relay 705 will release. The circuit of relay 707 is opened at armature 729 and that relay also releases. Relay 707 on restoring again disconnects the upper winding of relay 708 from the trunk circuit and relay 712 operates in series with the lower winding. The circuit lamp L2 is now closed at armature 743 and the lamp lights to give the operator disconnect supervision. Relays 705 and 709 also deenergize when the calling subscriber hangs up but have no effect at this time. The switch train in the main office is held up by ground from the trunk apparatus TA controlled by relay 704. The equipment in the sub-office, however, releases as in the previously described connection between a sub-office and a main office subscriber. The operator now removes the answering plug from the jack and relays 711, 712, 708 and 704 restore. Ground is removed from release trunk conductor 551 and selectors S₂ and S₃ and repeater DR restore to normal. The apparatus is now in condition to receive the next call.

A long distance connection from a restricted line in the sub-exchange would be completed in the same manner as the above-described connection, except that the intercepting operator would be required to set up the trunk switches in the main exchange as previously mentioned.

A local connection in the sub-exchange will now be described. Local calls may be completed automatically regardless of whether or not the calling line is restricted. It will be assumed that the subscriber at substation T is calling number 8425 which is the number assigned to substation T1 (Fig. 3). On lifting the receiver, the calling line is extended to repeater SR and by way of lineswitch DLS to repeater DR in the main exchange exactly as in the previous instances. The first digit dialled, i. e., the digit 8 is registered in repeater SR and operates selector S₂ or repeater DR (depending on whether or not the calling line is restricted) as previously described. It will be recalled that after the first series of impulses, wiper 165 restored to normal and relays 110 and 111 of repeater SR locked up to ground at armature 132. Repeater SR responds to the second series of impulses as do either selector S₂ or repeater DR as previously described. However, since the second digit dialled is the digit 4, wiper 165 will be advanced four steps and engage contact 167. Now, when relay 106 deenergizes shortly after the last impulse of the series, a circuit is closed

from ground, armature 141, wiper 165, contact 167, conductor 170, armature 154, armature 161, resistance 119 to battery. Relay 113 which had been locked up by way of armatures 159, 156 and 132 is shunted by the above circuit and retracts its armatures. The loop circuit over which the main-office switches are held is opened at armature 157, the local release trunk conductor is disconnected from conductor 173 and connected to conductor 174 at armature 158, the holding circuit of relay 113 is opened at armature 159, the impulsing circuit is connected to conductor 172 at armature 160, and the shunt circuit for relay 113 is opened at armature 161. Relay 114 deenergizes but is without effect at this time. Relay 109 energizes responsive to wiper 165 leaving its normal position, closes a point in the release circuit at armature 145, opens the circuit of stepping magnet 116 at armature 146, opens a point in the timing circuit at armature 147, and connects the busy tone to conductor 181 at armature 179. The utility of the latter operation will be explained hereinafter.

When ground is removed from conductor 173, relay 201 of lineswitch DLS restores, disconnects trunk conductors 171 and 175 from wipers 222 and 223 at armatures 217 and 220, opens a point in its own holding circuit at armature 270, removes ground from release trunk conductor 234 at armature 218, and opens another point in its own holding circuit at armature 219. Relay 301 of connector IC releases when ground is removed from conductor 234, this relay again connecting the incoming trunk to connector IC to enable that switch to respond to an incoming call. The ground on conductor 174 causes relay 202 to operate in its first step, thereby actuating armatures 213 and 215. Since the lineswitch had previously selected an outgoing trunk, wiper 224 will be standing on a permanently grounded contact. This ground will shunt the upper winding of relay 202 and at the same time cause the stepping magnet to operate and open its own circuit at interrupter springs 269. The magnet on restoring steps the wipers ahead to the next set of contacts which are associated with a local trunk. If this trunk is busy the above operations will be repeated. Assuming that the wipers stop on the trunk terminating on contacts 226-229 and that the trunk is idle, wiper 224 will encounter battery through relay 206. The stepping magnet and the lower winding of relay 202 will be shunted and relay 202 will operate in its second step, thereby actuating all of its armatures. Talking conductors 171 and 175 are then connected to battery and ground, respectively, through the windings of impedance coil 204 by way of armatures 212 and 216, wipers 222 and 223, and contacts 226 and 227. Impulsing conductor 172 is connected to the stepping magnet in a circuit which will be traced subsequently. A point in the circuit of stepping magnet 203 is opened at armature 213 and the magnet is connected in series with the upper winding of relay 202 at armature 215. A circuit is also closed from ground, armature 214, wiper 224, contact 228, relay 206 to battery. Relay 206 operates, opens a point in the releasing circuit at armature 241, disconnects one of the multiple grounds from relay 272 at armature 240, the purpose of which will be described later on, and at armature 242 disconnects ground from marking contacts 267 and 268 and connects it to the upper winding of relay 210. The apparatus is now ready to receive the third series of impulses. The calling subscriber now dials the digit 2, relay 103 responding in the usual way. Relay 105 also energizes during each series of impulses as in the previous instance, but this has no effect at this stage of the call. Relay 106 does not operate again since its circuit is open at armature 146. At each deenergization of relay 103 a circuit is closed from ground, armatures 130, 133 and 160, conductor 172, armature 279, wiper 225, contact 229, lower winding of relay 205, armatures 246 and 253, stepping magnet 211 to battery. The stepping magnet responds to each impulse and advances the wipers into engagement with the second set of contacts, (the digit 2 having been dialled). Relay 205 operates in response to the first impulse and short circuits its upper winding at armature 238. The relay is thereby rendered slow to release and remains operated throughout the series of impulses. Relay 205 on operating, at armature 236 completes an auxiliary impulsing path around armatures 246 and 253 to prevent a possible interruption of the impulsing circuit as the wipers pass over busy lines; at armature 237, opens a point in the alternate circuit of magnet 211, and closes a circuit for relay 207 by way of wiper 260, home contact engaged by this wiper, contacts controlled by armature 244, relay 207 to battery. The above circuit is closed and relay 207 operates before the wipers are stepped to the next set of contacts. Relay 207 locks to ground at armature 237 by way of armature 244 and closes a point in the alternate circuit of magnet 211 at armature 243. Shortly after the last impulse of the series, relay 205 deenergizes, removes the ground from wiper 260 and relay 207, and closes a point in the alternate circuit of the stepping magnet. It will be noted that the second to the ninth contacts enclosure with which wiper 260 engages are permanently grounded. At the end of the series of impulses, this ground by way of wiper 260, armatures 237 and 243, and the interrupter springs will cause magnet 211 to energize, interrupt its own circuit and step the wipers ahead to the next set of contacts. Since wiper 260 continues to encounter grounded contacts,

the stepping magnet will continue to operate in a buzzer like manner and advance the wipers into engagement with the eleventh set of contacts. Wiper 260 will now engage contact 268 which is dead, and the stepping action ceases. Relay 207 deenergizes and opens the alternate circuit of the stepping magnet so that there will be no automatic rotation after the final digit. The subscriber now dials the final digit, relay 103 responding in the usual way and repeating the impulses over conductor 172. Relay 205 and the stepping magnet respond as in the previous instance, and the wipers are advanced to the fifth set of contacts of the second group, on which the line from substation T1 terminates. If the called line is busy, wiper 259 encounters a ground on contact 266. This ground by way of armatures 245 and 239 causes relay 208 to energize, open the impulsing circuit at armature 246, and close a point in its own locking circuit at armature 247. Shortly after the last impulse of the series, relay 205 deenergizes and at contacts controlled by armature 239 completes the locking circuit for relay 208. Relay 208 connects busy tone to the trunk at armature 248. This tone is audible to the calling subscriber who is thereby informed that the wanted line is busy in another connection, and that it is necessary to hang up and call again.

In case the called line is idle there will be no ground on contact 266 and relay 208 will not operate. When relay 205 deenergizes shortly after the last impulse of the series a circuit is then closed from battery, through the cut-off relay corresponding to relay 11 of the called line, release trunk conductor 4', contact 266, wiper 259, armatures 245 and 239, upper winding of relay 210, armatures 247 and 242 to ground. Relay 210 and the cut-off relay energize over the above circuit, the cut-off relay disconnecting the normal battery and ground connections from the line so that the line relay will not operate when the called subscriber answers. Relay 210 closes a locking circuit for itself at armature 254, connects a holding ground to the release trunk at armature 255, and at armatures 252 and 256 connects the line conductors through. Ringing current is now sent over the line in the usual manner from grounded generator G, armatures 251 and 256, wiper 258, contact 265, conductor 2', through the bells and condenser at the called substation, conductor 3', contact 264, wiper 257, armatures 252 and 249, upper winding of relay 209 to battery. Relay 209 does not respond to alternating current. When the called subscriber answers a direct current path is closed for relay 209 and the relay operates. The ringing current is sent out intermittently under control of the interrupter INT which connects a ground to the ringing circuit during the intervals at which the ringing current is disconnected so

that relay 209 will operate immediately when the call is answered whether during a ringing period or a silent period. Relay 209 in operating closes a locking circuit for itself at armature 250, and at armatures 249 and 251 opens the ringing circuit and completes the talking circuit between the calling and called subscribers.

The slightly different operation of the connector when a subscriber in the first group is called may be pointed out at this time. In this case, the digit one is dialled and wipers 260 is stepped into engagement with contact 267 which is dead. When relay 205 restores after the impulse, relay 207 will no longer receive a holding ground and will also restore. The second series of impulses will then set the wipers on the proper contacts of the first group in the manner previously described.

When the subscribers finish talking and hang up their receivers, switching repeater SR releases as described in a previous connection. Ground being removed from conductor 174, relay 202 releases and the lineswitch DLS is again placed in normal condition. Ground is thereby removed from wiper 224 and relay 206 restores, closes a point in the alternate circuit of stepping magnet 211 at armature 241 and at armature 242 opens the locking circuits of relays 209 and 210 and connects a ground to contacts 267 and 268. All contacts engaged by wiper 260 are now grounded except the normal or "home" contact, stepping magnet 211 therefore operates buzzer-like as previously described, until the wipers have been moved to home position. The cut-off relay of the called line also releases and restores the normal battery and ground connections to the line.

Certain auxiliary features referred to in the foregoing paragraphs will now be considered. Referring to Fig. 1, it will be recalled that when the calling line was extended to repeater SR by finder switch F, the circuit of relay 13 was opened at armature 21. Relay 13 deenergized and relays 14 and 15 locked up in series. Now when another call comes in with the starting relays in this condition, a circuit is again closed for relay 13 at armature 21. Relay 13 operates and at armature 22 closes a circuit from battery, resistance 16, armature 27, relay 15 to ground. Relay 14 is shunted and deenergizes, thereby opening its own holding circuit at armature 25. The actuation of armature 23 is without effect since armature 26 is also actuated. Starting ground by way of armatures 24 and 28 is now connected to starting conductor 178 terminating in repeater SR''' which operates in the same manner as repeater SR in the previous connection. This arrangement insures against a calling subscriber receiving the same repeater on successive calls which is advantageous since a defective repeater

will not absolutely prevent the subscriber from getting service.

There is also an arrangement to care for all trunks busy condition. Assume that in 5 any of the previous calls all trunks between the sub-office and the main office were busy. In this case relays such as relay 301 or relay 305 would be operated depending on whether the trunks were engaged in outgoing or incoming calls. In either event, ground would 10 be disconnected from conductor 279 at all connectors to which this conductor is common. Relay 271 would deenergize and remove ground from contact 275 at armature 273. 15 Now when wiper 221 passes over the various contacts in search of an idle outgoing trunk the hunting operation will stop when the wiper reaches contact 275 (all other contacts being grounded). Relay 201 will operate as 20 in the previous instance and connect the speaking conductors through. Referring now to Fig. 1, relay 109 will be in normal position until the first digit is dialled and dial tone by way of armatures 180 and 179 25 will be connected to conductor 181. This tone will then be connected to the calling line by way of contact 277 and wiper 222 to inform the calling subscriber that dialling may proceed. If the first two digits identify the call 30 as outgoing, the wipers will remain in the same position but relay 109 will be operated and the dial tone will be replaced by a busy tone. The calling subscriber will, therefore, hang up and release the connection. If the 35 first two digits identify the call as a local one, lineswitch DLS hunts for a local trunk as previously described and the connection is completed without operating the main office apparatus. It is apparent that the dial tone is replaced by a busy tone as soon as the first 40 digit is dialled, but this is not objectionable since the calling subscriber does not ordinarily listen for a tone between digits.

In case all local connectors are busy, outgoing calls may be completed as in the previous instances. If the first two digits identify the call as local, lineswitch DLS will hunt over the banks for a local trunk as previously described. Since all local connectors 45 are busy, relays such as relay 206 will be energized and the multiple ground connections for relay 272 will be open at armatures such as armature 240. Relay 272 will consequently deenergize and disconnect ground from contact 276 at armature 274. When this contact 50 is encountered by wiper 224, the hunting action will cease and relay 202 will energize as in the previous instances. A busy tone will now be connected to the calling line by way 55 of conductor 183, contact 278 and wiper 222, thereby informing the calling subscriber that the wanted line is not available at the present time.

The connections dealt with in the foregoing 60 pages were for calls originating in the

sub-office. Calls to sub-office subscribers from the main office and manual office will now be considered. Assume first that a subscriber at substation T2 at the main office calls number 8425 assigned to substation T1 at the sub-office. On lifting the receiver, a loop is closed for line relay 502 of lineswitch LS. This switch is of the ordinary rotary type having no normal or "home" position, the operation of which is well known and will not be described in detail. The lineswitch hunts for and connects with an idle trunk to a first selector such as the trunk comprising conductors 519-521 terminating in first selector S. Selector S operates in the well known manner in response to the first digit and advances its wipers 522-524 to the eighth level where an idle trunk to a second selector is seized. Assume that the seized trunk is the trunk comprising conductors 528-530 terminating on contacts 525-527 and extending to selector S3. Selector S3 operates in response to the second digit, the digit 4, and wipers 531-533 are advanced to the fourth level where an idle trunk to the sub-exchange is selected. This trunk may be the trunk comprising conductors 552-554. The calling line is extended to relay 456 through the two windings of relay 464. The two windings of relay 464 oppose each other and the relay does not operate over the loop. Relay 456 operates, closes a point in the loop circuit to the sub-exchange at armature 459, and at armature 460 closes an obvious circuit for relay 457. Relay 457 operates and at armature 461 connects ground to release trunk conductor 553 to hold up the preceding switches and relay 401. Relay 401 operates from ground on the release trunk as soon as the trunk is seized and at armatures 414 and 415 disconnects the incoming trunk conductors from line relay 406 of repeater DR and connects them to the impulsing contacts of relay 456 by way of impedance 458. Relay 457 is made slow to release so that it will hold up when its circuit is momentarily interrupted during impulsing. Impedance 458 is used to improve transmission over the trunk and is preferably an impedance which offers a low resistance to direct current and a relatively high resistance to voice currents. The talking conductors of the incoming and outgoing trunks are inductively connected by condensers 462 and 463.

Selector S3 having seized a trunk as above, 121 a loop circuit is extended to incoming connector IC (Fig. 3) which may be traced as follows: battery, upper winding of relay 304, upper winding of relay 303, contact controlled by armature 316, armature 314, trunk conductor 352, armature 414, impedance 458, armatures 459 and 415, trunk conductor 353, armature 315, contacts controlled by armature 317, lower windings of relays 303 and 304 to ground. Relay 303 is constructed with 122

opposing windings similar to relays 405 and 464 previously described. Relay 304 energizes over the above loop circuit and closes a circuit for relay 305 in series with stepping magnet 313 at armature 319. Relay 305 energizes but the magnet does not due to the high resistance of relay 305. Relay 305 connects ground to the local release trunk at armature 354; opens a point in the homing circuit of the stepping magnet and closes a point in the circuit of relay 306 at armature 320; disconnects relay 301 from release trunk conductor 234 and connects a ground there-to at armature 321 to mark the trunk busy to lineswitch DLS; and disconnects ground from special bank contacts 267' and 268' and closes a point in the impulsing circuit at armature 322. The calling subscriber now dials the third digit of the called number, 20 i. e., the digit 2, and relay 456 of repeater DR responds and interrupts the loop extending to relay 304. Relay 304 responds to the impulses and each time armature 319 drops back a circuit is closed from ground at contacts controlled by that armature, armatures 322, 331 and 345, magnet 313 to battery, and in parallel therewith through relay 307 to battery. Relay 305 is short circuited by the above ground which renders the relay slow 25 to release and permits it to maintain its operated position during the impulsing. The stepping magnet responds to each impulse and advances the wipers ahead to the second set of bank contacts (digit 2 dialled). Relay 307 energizes responsive to the first impulse, closes an additional impulsing circuit around armatures 331 and 345 at armature 328; closes a point in the circuit of relay 308 at armature 327; and closes a point in the 30 circuit of relay 306 at armature 326. The circuit of relay 306 is closed before the wipers are moved from the home position and extends from ground, armature 326, armature 320, wiper 351, home bank contact engaged 35 by the wiper, contacts controlled by armature 325, relay 306 to battery. Relay 306 energizes, closes a point in the auxiliary stepping circuit at armature 323, opens a point in the test circuit at armature 324, and closes a locking circuit for itself including wiper 351 but independent of the home contact at armature 325. Shortly after the last impulse of the series relay 307 deenergizes as the resistance of relay 305 is such that relay 307 50 will not remain energized in series therewith. This circuit, however, slows up the release of relay 307 so that it remains operated throughout the series of impulses. A circuit is now closed from permanently grounded contact of the bank, wiper 351, armature 320, armature 326 and its resting contact, armature 323, interrupter springs 347, magnet 313 to battery. Relay 306 also remains locked to the above ground. The stepping magnet 55 operates buzzer like as described for connector LC and steps the wipers around to the eleventh set of contacts and wiper 351 engages contact 268'. This contact is now dead since relay 305 is operated, hence the circuit of the stepping magnet and relay 306 is 70 opened. The wipers therefore stop on this set of contacts and relay 306 deenergizes. Relay 306 opens the auxiliary stepping circuit and its own locking circuit and closes the testing circuit. The wipers of the connector are now standing before the contacts of the second line group and the connector is ready to receive the last series of impulses. The calling subscriber now dials the digit 5 which is repeated to relay 304 as in the previous instance and relay 304 responds. Relay 307 and the stepping magnet again operate as before and the wipers are advanced five steps to contacts 264'-266' terminating the line from substation T1. 75

In case this line is busy, wiper 350 will find ground on contact 266' and relay 308 will energize over a circuit including armature 324 and armature 327 and its working contact. When relay 307 falls back shortly after the last impulse of the series, a locking circuit for relay 308 will be completed by way of 334 and 330, and contacts controlled by armature 327. Relay 308 opens the impulsing circuit at armature 331, and at armature 332 connects a busy tone to the lower talking conductor to inform the calling subscriber that the called line is busy. 80

If the calling line is idle, wiper 350 finds battery through a cut-off relay such as relay 11 on contact 266' and relay 308 does not operate. When relay 307 deenergizes shortly after the last impulse of the series relay 312 and the cut-off relay of the called line energize in series the circuit extending 90 through wiper 350, armatures 324 and 327, lower winding of relay 312, armature 330 to ground at armature 354. Relay 312 closes the ringing circuit at armatures 342 and 346, connects the test wiper to the grounded local release trunk at armature 343, closes a locking circuit for its own upper winding at armature 344, and opens a point in the impulsing circuit at armature 345. Grounded generator and direct ground are now alternately connected to line conductor 2' by way of armatures 339 and 346, wiper 349 and contact 265' and through the bells and condenser at the called substation to line conductor 3', contact 264', wiper 348, armatures 342 and 337, lower winding of relay 310 to battery. The bells at the called substation are rung intermittently as is the usual practice. Relay 310 is an ordinary ring cut-off relay constructed so as to be unresponsive 100 to alternating or pulsating current such as is used for ringing purposes but operative when a direct current circuit is closed for it. When the called subscriber answers, relay 312 operates, closes a locking circuit for its upper 105 110 115 120 125 130

winding at armature 338, and at armatures 337 and 339 disconnects the ringing current for the line and completes the talking circuit. Back bridge relay 302 feeds battery to the called subscriber and operates over the called subscriber's loop to reverse battery over the trunk in the usual manner. Battery reversal has no utility in this case but may be used for metering or supervisory purposes in a number of ways which are well known in the art.

When the called subscriber hangs up, relay 302 releases and reverses battery on the trunk back to normal. When the calling subscriber hangs up, the loop to relay 456 is opened and that relay releases followed by the releasing of relays 457 and 401. Ground is removed from release trunk conductor 553 and the selectors and lineswitch in the main office restore to normal in the usual way. The restoration of relay 456 opens the loop to relay 304 which releases. Relay 305 releases and removes ground from the local release trunk whereon relays 310 and 312 also release. Relays 304 and 305 on restoring again connect ground to contacts 267' and 268' so that all contacts engaged by wiper 351 except the "home" contact are grounded. The stepping magnet now operates as previously described for the local connector over a circuit from grounded contacts engaged by wiper 351, armature 320 and its resting contact, interrupter springs 347, magnet 313 to battery and the wipers are stepped to home position.

A call from the manual operator to substation T1 in the sub-exchange will now be described. The operator first inserts the plug of cord AC in the jack of an idle trunk, for instance the jack J', thereby closing a circuit for relay 711 of position equipment TM. Relay 711 closes a circuit from battery, armature 740, relay 712, contacts controlled respectively by armatures 745 and 744, conductor 750, left hand windings of repeating coil R4, trunk conductors 757 and 758 in parallel, armatures 720 and 721, left hand windings of repeating coil R3, contacts controlled by armature 732, lower winding of relay 708 to ground at armature 723. Relays 712 and 708 energize in series over the above circuit, relay 712 closing a circuit for lamp L2 which lights. Relay 708 closes a circuit for relay 704 at armature 733, and closes a loop to incoming selector S1, at armature 755. Relay 704 operates, extends a holding ground over release trunk conductor 748 at armature 725; closes a point in the circuit of relay 703 at armature 726; connects a busying ground to release trunk conductor 551 and disconnects relay 709 therefrom at armature 716 and contacts controlled thereby; disconnects relay 702 from the local holding conductor and grounds the conductor at armature 728; and

at armature 727 disconnects relay 701 from incoming release trunk conductor 672 and connects ground to that conductor to mark the trunk busy to finder links FL. A circuit is now completed for the upper winding of relay 707 from ground at armature 728, resistance 717, and armature 731. Relay 707 does not energize under the above conditions as was previously explained. The lower winding of relay 707 is bridged across trunk conductors 746 and 747 by way of armatures 736 and 737, right hand windings of repeating coil R3, and armatures 735 and 738. The above trunk conductors extend to the line relay (not shown) of selector S1 and the line relay energizes. The direction in which current flows through the lower winding of relay 707 is such that the two windings oppose each other and the relay does not actuate its armatures.

The operator now inserts the plug of dialing cord DC in jack J and dials the number of the called subscriber which is assumed to be number 8425. As the dial is turned off-normal, contacts 754 close and complete a circuit for relay 713 by way of the ring of the plug and jack. Relay 713 actuates its armature 744 and substitutes battery through the impulsing contacts of the dial for battery through relay 712 on the simplex circuit. As the dial returns to normal, the impulsing contacts interrupt the circuit in the usual way and relay 708 responds by deenergizing and reenergizing at each interruption. Relay 708 interrupts the loop to selector S1 at armature 755, thus repeating the impulses to that selector, and at armature 733 completes a circuit for slow to release relay 703. Relay 703 operates and maintains its armatures in operated position throughout the series of impulses. A circuit is now closed for relay 763 at armature 766 and that relay operates. Shortly after the last impulse of the series, relay 708 remaining energized opens the circuit of relay 703 and that relay releases. As armature 766 drops back, ground is connected to the positive trunk conductor 747 by way of armatures 764 and 765. Relay 763 being slow to release, remains operated a short time after its circuit is opened at armature 766. Relay 763 then restores to normal and disconnects the ground from conductor 747.

The above operations take place in the operator's equipment and trunk apparatus as each digit is dialled. Selector S1 responds to the first digit in the usual way, steps its wipers to the called level, selects an idle trunk which will be assumed to be the trunk comprising conductors 528—530, and extends the control loop to the line relay of selector S3. Selector S3 responds to the second digit in the same manner and extends the loop to an outgoing repeater, for example the repeater 130

DR. Relay 456 operates over the control loop as in the previously described call from substation T2 to substation T1 and extends a control loop to incoming connector IC in the sub-exchange. Relay 304 of connector IC operates over the above loop and functions exactly as described in the previous connection. The impulses of the third digit are repeated by relays 708 and 456 and relay 304 responds in the usual way to advance its wipers to the second set of contacts (digit 2 dialed). Shortly after the last impulse of the series, ground is momentarily connected to the positive trunk conductor as previously mentioned, thereby unbalancing relay 464 by shunting its lower winding. Relay 464 operates momentarily and unbalances the trunk to the sub-exchange by momentarily grounding positive trunk conductor 353. Relay 303 now operates from the unbalanced condition of the trunk and closes a circuit for relay 309 at armature 318. Relays 464 and 303 remain operated only during the short interval during which the trunk is unbalanced. Relay 309 operates and locks to ground on the local holding conductor at armature 335. The automatic stepping action previously described now takes place and wipers 348-351 are advanced to the contacts of the second group of lines. The connector responds to the last digit as in the previous connection and the wipers are set on the contacts of the called line. It will be recalled that relay 307 operated with each series of impulses and prepared certain circuits. If the called line is busy, a circuit is closed for relay 308 before relay 307 drops back and relay 308 energizes. Relay 307 releases and completes a locking circuit for relay 308, this time to ground on the test contact of the busy line since relay 309 is operated. Relay 307 on releasing also closes a circuit from ground, contacts controlled by armature 326, armatures 329 and 333, relay 311 to battery. Relay 311 operates and completes an auxiliary talking circuit at armatures 340 and 341. There will be no busy tone on the line since armature 336 is actuated. The operator may now talk with the subscriber using the line and advise him that a toll call is waiting. Both subscribers will then hang up their receivers, releasing the switches in the local connection and removing the ground from the test contact of the wanted line. Relay 308 now de-energizes since it was locked to ground on the test contact, opens the circuit of relay 311 and closes a point in the circuit of relay 312. Relay 311 releases and opens the auxiliary talking circuit. Relay 312 and the cut-off relay of the called line operate and ringing current is impressed on the line in the same manner as in the previously described connection. The ringing circuit is opened and the talking circuit completed when the

called subscriber answers in the usual manner.

In case the called line is idle when the connection is extended, the connector switches through and signals the called subscriber in the usual way, the operated condition of relay 309 having no effect in this instance. When the calling subscriber hangs up and the operator withdraws the answering and calling plugs from the jacks, the equipment releases as described in previous connections.

The manner in which calls between main office subscribers and the operator are completed will be obvious from the foregoing explanations. The operation of the trunk equipment is the same in either case. The only difference in operation will be the elimination of apparatus in the sub-exchange. Selector S3, instead of selecting a trunk to either manual or sub-exchange will be operated to a local level and will select a trunk to a local connector, such as connector C, the operation of which is well known.

Having described this invention, what is considered new and is desired to have protected by Letters Patent will be pointed out in the appended claims.

What is claimed is:

1. In a telephone system, a universal switcher, a trunk selecting switch associated therewith, local and outgoing trunks accessible to said switch, means responsive to the extension of a call to said switcher for operating said switch to select an idle outgoing trunk, and means controlled by a registering device in the switcher for reoperating said switch to select an idle local trunk.

2. In a telephone system, a universal switcher comprising a digit register, a trunk selecting switch having access to trunks of two classes, means in the switcher responsive to its seizure for operating said switch to select an idle trunk of one class, and means in the switcher responsive to the registration of a plurality of digits for reoperating said switch to select an idle trunk of the other class.

3. In a telephone system, a universal switcher comprising a digit register, a trunk selecting switch having two hunting movements, two relays in said switch for controlling the respective hunting movements thereof, means responsive to the seizure of the switcher for operating one of said relays, and means responsive to the registration of a particular series of digits for operating said other relay.

4. In a telephone system, a universal switcher including a digit register, a trunk selecting switch, two control conductors extending to said switch, means for operating said switch over one of said conductors responsive to the seizure of the switcher, and means for reoperating said switch over the

- other of said conductors responsive to the registration of a particular series of digits.
5. In a telephone system, a switching device including a digit register, a trunk selecting switch associated therewith, two classes of trunks accessible to said switch, means in the device responsive to the extension of a call thereto for operating said switch to select an idle trunk of one class, and means in the device responsive to the registration of certain digits for reoperating said switch to select an idle trunk of another class.
6. In a telephone system, a switching device including a digit register, two relays in said device, a trunk selecting switch having access to trunks of two classes, means responsive to the seizure of said device for operating said switch to select an idle trunk of one class, means responsive to the registration of a particular digit for operating one of said relays and for releasing the register, and means responsive to the registration of a second particular digit for operating said other relay whereby said switch is reoperated to select an idle trunk of the other class.
7. In a telephone system, a universal switcher including a digit register, local and outgoing trunks, contacts associated with said trunks, a trunk selecting switch having access to said trunks by way of said contacts, said switch being adapted to remain on the contacts of the trunk last used, means responsive to the seizure of the switches for operating said switch to first move to contacts of a local trunk providing the switch is initially standing on contacts of an outgoing trunk and to then hunt for and select an idle outgoing trunk, and means whereby said first operation is prevented when the switch is initially standing on contacts of a local trunk.
8. In a telephone system including a main exchange and a sub-exchange, trunks connecting the exchanges, means including a switching device in the sub-exchange for extending a calling sub-exchange line to the main exchange via one of said trunks responsive to the initiation of a call, means in the main exchange for returning a dial tone to the calling subscriber, and means in said device for returning a similar dial tone to the calling subscriber providing all trunks to the main exchange are busy.
9. In a telephone system including a main exchange and a sub-exchange, trunks connecting the exchanges, means including a switching device in the sub-exchange for extending a calling sub-exchange line to the main exchange via one of said trunks responsive to the initiation of a call, means in the main exchange for returning a dial tone to the calling subscriber, and means in said device for returning a similar dial tone to the calling subscriber providing all of said trunks are in use, and means in said device for substituting a busy tone for the dial tone in case the call is for a subscriber in the main exchange.
10. In a telephone system, a temporarily established connection including an impulse repeater, a lineswitch and an outgoing trunk, means for transmitting series of digit impulses over said connection, and means in said repeater responsive to the transmission of a particular series of digits for releasing said temporary connection and for establishing another connection including said repeater, said lineswitch, and a local trunk.
11. In a telephone system including a main exchange and a sub-exchange, two classes of lines in the sub-exchange, a switching device and a selector switch in the main exchange, means for automatically extending a call from a line of either class to said device, and means in the device for further extending a call to said switch providing the calling line is of one particular class.
12. In a telephone system including a main exchange and a sub-exchange, two classes of lines in the sub-exchange, a switching device in the main exchange, two trunks outgoing from said device, means for automatically extending a call from a line of either class to said device responsive to the initiation of the call, means in the device for further extending the call via the first of said trunks if the calling line is of one class, and means in the device for further extending the call via the second of said trunks if the calling line is of the other class.
13. In a telephone system including a plurality of exchanges, two classes of lines in one exchange, a switching device in another exchange, a local trunk and an intercepting trunk associated with said device, means for automatically extending a call from a line of either class to said device responsive to the initiation of a call, means in the device responsive when the calling line is of one class for further extending the call via said local trunk, and means in the device responsive when the calling line is of the other class for further extending the call via said intercepting trunk.
14. In a telephone system, a trunk, a directly controlled switch associated with the trunk but normally disconnected therefrom, a switching device terminating the trunk, an operator's position, means in said device responsive to certain calls over said trunk for connecting the trunk to said switch and for placing the switch under control of the calling subscriber, and means in the device responsive to other calls over said trunk for extending the call to said position and for placing said switch under control of the operator.
15. In a telephone system including three exchanges, trunks connecting the first and second and the second and third exchanges, lines of two classes in the first exchange,

- means responsive to the initiation of a call from a line of either class for extending a connection to the second exchange, switching mechanism in the second exchange controlled by the calling subscriber for further extending the connection to the third exchange providing the calling line is of one class, and switching mechanism in the second exchange for automatically extending the connection to the third exchange providing the calling line is of the other class. 10
16. In a telephone system, an operator's position and a trunk terminating therein, a signal associated with the trunk, two classes of lines having access to said trunk, means for extending a call from a line of either class over said trunk and for operating said signal, means for answering the call, and means responsive to the answering of the call for disabling said signal only when the calling line is of one class. 15
17. In a telephone system including three exchanges, lines of two classes in the first exchange, an operator's position in the third exchange, switching mechanism in the second exchange controlled by the calling subscriber for completing a connection to a called subscriber in the second exchange from a line of one class, other switching mechanism in the second exchange for automatically extending a calling line to said position when a calling subscriber attempts to complete a connection to a called subscriber in the second exchange from a line of the other class, and means controlled by the operator for completing the attempted connection to the called subscriber and for disconnecting the connection to said position. 25
18. In a telephone system, a trunk selecting switch, circuit arrangements for placing said switch under the control of a calling subscriber on certain calls, other circuit arrangements for placing the switch under the control of an operator on other calls, and means controlled by the operator for disabling said second circuit arrangement and for transferring the control of the switch to the calling subscriber. 40
19. In a telephone system including an operator's position, a trunk, a selector switch associated with said trunk but normally disconnected therefrom, a link circuit, means responsive to a call over the trunk for operating said link to connect with the trunk and the associated selector, means in the link for further extending the call to the operator's position, means controlled by the operator for directly operating the switch to further extend the call, and means controlled by the operator for disconnecting the trunk from said link and for connecting it directly to said switch. 55
20. In a telephone system including an operator's position, a trunk comprising two normally disconnected sections, a link circuit, means responsive to a call over one of said trunk sections for operating said link to hunt for and connect with both of said sections and to extend the call to the operator's position, means controlled by the operator for completing the call over the other of said trunk sections, and means controlled by the operator for connecting the said two trunk sections independent of said link. 70
21. In a telephone system including an operator's position, three trunks, means for extending a call via the first and second of said trunks to the position, means controlled by the operator for further extending the call via the second and third of said trunks, and means under the control of the operator for completing the talking connections via said second trunk with either the first or the third trunk at will. 75
22. In a telephone system, three trunks, means responsive to certain calls over the first trunk for automatically extending the call over the second trunk, means responsive to other calls over the first trunk for automatically extending the call over the third trunk, and means controlled over the third trunk for transferring the call to the second trunk and for releasing the third trunk. 80
23. In a trunk selecting switch having access to trunks of two classes, two two-step relays, means responsive to the operation of one of said relays in its first step for operating the switch to select an idle trunk of one class, means responsive to the operation of the other of said relays in its first step for operating the switch to select an idle trunk of the other class, and means responsive to the selection of an idle trunk for operating the relay used in its second step. 85
24. In a two-digit connector having access to a plurality of groups of lines, an automatic stepping circuit for restoring the wipers of the connector to home position, and circuit arrangements whereby said stepping circuit is rendered effective responsive to the receipt of the first impulse of the first digit but before the wipers initially leave the home position to advance the wipers into selective relation with a called line group. 105
25. In a two-digit connector, a stepping magnet, a line relay for operating said magnet to advance the switch part of the way to a group of contacts, means including a wiper and a row of contacts for advancing the switch the rest of the way to said group, and means including said wiper and said contacts for restoring the switch. 110
26. In a two-digit connector, two groups of contacts, means responsive to the first digit if it has a particular value for positioning the switch adjacent to the first group of contacts, and means responsive to any first digit having a greater value for positioning the switch adjacent to the second group of contacts. 120
27. In a two-digit connector, two groups of contacts, means responsive to the first digit if it has a particular value for positioning the switch adjacent to the first group of contacts, and means responsive to any first digit having a greater value for positioning the switch adjacent to the second group of contacts. 125
28. In a two-digit connector, two groups of contacts, means responsive to the first digit if it has a particular value for positioning the switch adjacent to the first group of contacts, and means responsive to any first digit having a greater value for positioning the switch adjacent to the second group of contacts. 130

- contacts, means responsive to the first digit for positioning the switch adjacent the first group or on a contact of the first group depending on the value of the digit, and means for automatically advancing the switch to another group whenever the first digit positions the switch on a contact of the first group.
28. In a two-digit connector, two groups of contacts, means responsive to the first digit for positioning the switch adjacent the first group or on a contact of the first group depending on the value of the digit, means for automatically advancing the switch to another group whenever the first digit positions the switch on a contact of the first group, and means for rendering said last means effective to restore the switch.
29. In a telephone system, a two-digit connector, a wiper for the connector, line contacts, group contacts and a home contact engaged by said wiper, an automatic stepping circuit for positioning the wiper on the contact of a called group, a relay for controlling said circuit, means including said wiper and the home contact for operating said relay responsive to the receipt of an impulse of the first digit, and means including said wiper and said line contacts for maintaining said relay operated until the wiper is positioned on a group contact.
30. In an automatic telephone system including a universal switcher adapted to complete a control loop responsive to its seizure and to repeat dialled impulses thereover, means for automatically disconnecting the control loop, and means for disabling said other means responsive to the receipt of impulses within a preestablished time interval after the seizure of the switcher.
31. In a telephone system, three relays, means responsive to the initiation of a call for operating the first and second of said relays, means responsive to the extension of the call for releasing the first relay and for operating the third relay, means responsive to the initiation of a second call for reoperating the first relay and for releasing the second relay, and means responsive to the extension of the second call for releasing the first and third relays.
32. In a telephone system, a starting device comprising a plurality of relays, two starting circuits, means responsive to the initiation of a call for operating one combination of said relays to render one of said starting circuits effective, and means responsive to the initiation of a second call for operating another combination of said relays to render the other of said starting circuits effective.
33. In a non-numerical trunk selecting switch equipped with a single set of talking wipers and two test wipers, two test relays, a first hunting circuit including one of said test wipers and normally closed contacts of both of said relays, and a second hunting circuit including the other of said test wipers and normally closed contacts of only one of said relays.
34. In a non-numerical trunk selecting switch equipped with a single set of talking wipers and two test wipers, a two-step combined test and switching relay for connecting up said talking wipers and one of said test wipers, and a second two-step combined test and switching relay for connecting up said talking wipers and the other of said test wipers.
35. In a non-numerical trunk selecting switch equipped with a single set of talking wipers, a control wiper and two test wipers, a switching relay for connecting up the talking wipers and one of said test wipers, and a second switching relay for connecting up the talking wipers, said control wiper, and the other of said test wipers.
36. In a telephone system, a universal switcher, a non-numerical trunk selecting switch associated therewith, a single set of talking wipers for said switch, local and outgoing trunks accessible to said wipers, means responsive to the extension of a call to said switcher for operating said switch to connect said wipers to an idle outgoing trunk, and means in the switcher for re-operating said switch to connect said wipers to an idle local trunk.
37. In a telephone system, a trunk line extending from a manual switchboard to an automatic exchange and having three branches at the exchange end, an incoming selector terminating the first of said branches, local selectors for extending calls from said automatic exchange over the trunk via the second of said branches, a finder switch link for extending calls from another exchange over said trunk via the third of said branches, and means at the switchboard for indicating the branch over which a call is extended.
